Primary Examiner — Philip S Hyder*Assistant Examiner* — Roselynne Cody(74) *Attorney, Agent, or Firm* — Ryan Kromholz & Manion, S.C.**CLAIM**

(57) The ornamental design for a cable tie tensioning and cut-off tool, as shown and described.

DESCRIPTION

FIG. 1 is a front left side perspective view of the cable tie tensioning and cut-off tool;

FIG. 2 is a rear right side perspective view thereof;

FIG. 3 is a left side elevation view;

FIG. 4 is a right side elevation view;

FIG. 5 is a top plan view thereof;

FIG. 6 is a bottom plan view thereof;

FIG. 7 is a front elevation view thereof; and,

FIG. 8 is a rear elevation view thereof.

The broken lines in the drawings illustrate features and linear detail that form no part of the claim.
